(57) **CLAIM**

I claim the ornamental design for a storage container, as shown and described.

DESCRIPTION

FIG. 1 is a perspective view of a storage container showing the new design.

FIG. 2 is a top plan view thereof.

FIG. 3 is a front side elevational view thereof; the rear side elevational view being identical to the front side elevational view.

FIG. 4 is a bottom plan view thereof; and,

FIG. 5 is a left side elevational view thereof; the right side elevational view being identical to the left side elevational view.

The broken lines shown in FIGS. 1, 3, and 5 represent portions of the storage container that form no part of the claimed design.
